US00D608821S

(12) United States Design Patent
Tomono et al.

(10) Patent No.: US D608,821 S
(45) Date of Patent: * Jan. 26, 2010

(54) PRINTER

(75) Inventors: Satoshi Tomono, Suginami-ku (JP);
Yuki Shibata, Minato-ku (JP)

(73) Assignee: Konica Minolta Business Technologies, Inc., Chiyoda-Ku, Tokyo (JP)

() Term: 14 Years

(21) Appl. No.: 29/325,433

(22) Filed: Oct. 1, 2008

(30) Foreign Application Priority Data

Apr. 4, 2008 (JP) D2008-008738

(51) LOC (9) Cl. 14-02

(52) U.S. Cl. D18/50

(58) Field of Classification Search D18/36-37,
D18/50, 54, 54.1, 55, 19; D14/420-425,
D14/463-470; 400/613, 613.1-613.4, 690.1-690.4,
400/691-694

See application file for complete search history.
